UNITED STATES PATENT OFFICE

163,248

AWARD TROPHY

William A. Borba, South San Francisco, Calif.

Application July 16, 1949, Serial No. 3,957

Term of patent 14 years

(Cl. D29—23)

To all whom it may concern:

Be it known that I, William A. Borba, a citizen of the United States of America, residing at 524 Spruce Avenue, South San Francisco, California, have invented a new, original, and ornamental Design for an Award Trophy, of which the following is a specification, reference being had to the accompanying drawing, forming part thereof, in which

The dominant features of my design reside in the portion shown in full lines.

I claim:

The ornamental design for an award trophy, substantially as shown and described.

WILLIAM A. BORBA.
